DEVICE FOR CUTTING OR TRIMMING
WALLPAPER AND THE LIKE

Arthur Alexander Gelleff, Isleworth, England

Application April 19, 1935, Serial No. 17,342
In Great Britain April 20, 1934

6 Claims. (Cl. 164—83)

This invention relates to the trimming or cutting appliances for paper and the like, especially for use in trimming edges of wallpaper.

The object of the present invention is to provide an improved appliance which will be durable, simple to use and construct, and may be cheaply manufactured and operated, also providing an adjustable and removable blade which can be renewed at extremely low cost when necessary.

Other objects provide a means to smooth out kinks and irregularities in the paper selvedge to be cut, and guide the blade when drawn along the edge of paper. The length of the channel bottom also bridging over any damaged selvedge, thus preventing the cutting blade following the distorted outline where this is less in length than the guide. The blade can be placed in four different positions before it need be scrapped; furthermore the device cannot spoil the main body of the paper if misused for the blade can only run outward and not inward. The appliance can also be used by a left- or right-handed person without alteration.

With the above object in view I construct a handle in which a deep groove or channel of narrow limits in height is formed, the bottom of which guides the blade when drawn or pushed along edge of paper, the top and bottom members of this groove also smoothing out any irregularities in the paper before cutting; also holding the paper fairly firmly when the blade first strikes the paper. The device has also a block, an adjustable slide and blade holder combined, and an opening or series of slots in the handle to allow the blade to project through.

In the drawings:

Figure 1 is a front elevation.

Figure 2 is a plan view of the complete trimmer.

Figure 3 is an end view showing the bottom of the groove employed for guiding the blade along the paper edge.

Figure 4 is a rear elevation.

Figure 5 is a plan view of the handle and showing the slots.

Figure 6 is an end view showing the blade holder set at an angle.

Figure 7 is a plan view of the handle cut and shaped before bending.

Figure 8 is a front elevation of the handle showing the alternative shape of the blade bracket.

Figure 9 is a plan view of the combined slide and blade holder before shaping.

Figure 10 is a perspective view.

Figure 11 shows the blade cover.

Figure 12 is a perspective view of the trimmer with all bending operations reversed.

Figure 13 is a perspective view of the modified trimmer.

Like numerals of reference designate like parts throughout the several views.

Referring to the drawings *a* is the handle, which is sheet metal cut and shaped as shown at Fig. 7, and bent upon itself to form the groove *b*. Upon the top member *l* of this groove a block *c* is formed as shown at *c* into which a screw *i* is inserted to provide a fixing for the adjustable blade holder by means of the wing nut *h*. This block does not continue right across the top member but sufficient material is cut away to give the blade holder any predetermined measure of adjustment, and is to provide a runner for the adjustable slide.

The adjustable slide *d* is constructed in sheet metal (Fig. 9) and shaped to fit the block, a slot *y* being provided for adjustment. To this slide is formed at right angles a blade holder *e* which holds the blade edge at a cutting angle of 45 degrees to the paper, but this angle is not critical for any angle between 10-170 degrees could be used. A hole is provided in the approximate centre of this blade holder together with two projections *x* to engage in the holes of the 3 holed safety razor blade. The blade *f* is fixed to the holder by means of a screw and knurled nut *o*, the blade cover *g* Fig. 11 first being added before screwing on the knurled nut.

The opening *k* in the handle through which the blade passes can be either a complete cut-out, or a series of slots as shown at *m* in Fig. 5, the webs *n* supporting the paper each side of the blade. On the underside of the handle a further blade protector is formed *p* from the material forced down when constructing the opening in the bottom member. Figs. 7, 8, 10, 12, 13 show an alternative fixing and shape of this blade protector.

A further blade holder *d'*, *e'* will also be manufactured, Fig. 6, which gives a bevelled or mitred edge to the paper for the purpose of forming an invisible joint when the paper is attached to the walls. This modification is substituted for *d* of Figures 1 to 5 when it is desired to cut the paper with said bevelled edge.

In Fig. 5 the handle is shown with the blade and blade holder removed for the purpose of exposing the slots *m* which are cut into the top and bottom members of the handle.

It should be noted that the groove in the han-

de is not to exceed in height more than double the average thickness of the paper to be cut, particularly at the blade end.

The method of using the device is as follows:

5 The blade is first set to give the required width of cut by means of the adjustable slide and wing nut; the device is then slipped on to the edge of the paper until the paper edge is in contact with the guide formed by the bottom of the 10 groove *b*; the device is then gently drawn along the edge of the paper, care being taken to ensure that the paper is always in contact with the guide *s*. It is also intended to reverse all bending operations on the cut shapes Figs. 7 and 9 of 15 the handle, block and combined slide and blade holder, also the projections for steadyng the blade, the trimmer would now appear as shown in Fig. 12 with the combined slide and blade holder shown at *x*, and when used is pushed 20 along the selvedge with the blade and associated parts at the rear of the trimmer.

The trimmer shown in Figs. 1, 2, 4 and 10 is designed to pull along the edge of the paper.

Generally speaking, the invention can be considered as a handle member of channel section having an adjustable blade fitted at or near the end of the channel, and although I have described the construction of this device as manufactured in sheet metal, it must not be considered to be so limited as a suitable handle could be formed by channelling in wood, or any other solid material such as die casting of metal alloys, or moulded in a substance known under the registered trade-mark "Bakelite", or the like.

35 A modification of the invention may consist of having the blade fixed to give one width of cut only, say $\frac{3}{4}$ of an inch, this being the average width of the wallpaper selvedge, or the blade could be fixed, and the bottom of the groove 40 which is the blade guide, could, by the addition of a strip of material be made adjustable.

In the foregoing description the block *c* was placed in line with the opening *k* in the handle and thus restricted the movement of the blade 45 holder across the handle. A modification consists of placing the block *c'* in front of the opening, and reshaping the combined slide and blade holder to that shown at *p'* in Fig. 13. The blade will then be free to travel across the total width 50 of the top member.

By this invention I provide a very simple construction whereby the blade edge can be used in four different positions before it is necessary to scrap same, also providing means of easily adjusting the blade, also supplying an additional blade holder when a mitred edge is desired.

What I claim is:—

1. An edge trimmer for paper and like materials, comprising a base part formed of a single 60 sheet of material bent upon itself serving as a handle and guide, a transversely adjustable slide carried by said base part, and a blade rigidly carried by said slide with a cutting edge inclined

to and projecting into the guide to intersect the plane of material therein.

2. An edge trimmer for paper and like materials, comprising a base part formed from a single sheet of material bent back upon itself, the inner 5 part of the bend serving as the edge of a guide formed by the base; a transversely adjustable slide carried by said base part, and a blade rigidly carried by said slide with a cutting edge inclined to and projecting into the guide to intersect 10 the plane of material therein.

3. An edge trimmer for paper and like materials, comprising a base part formed from a single sheet of material bent back upon itself, the inner 15 part of the bend serving as the edge of a guide formed by the base, the upper folded back part of said base having cut away adjacent the fold a piece of material in order to provide a space through which the blade may pass to enter the guide; a transversely adjustable slide carried by 20 said base part and a blade rigidly carried by said slide with a cutting edge inclined to and projecting into the guide to intersect the plane of material therein.

4. An edge trimmer for paper and like materials, comprising a base part formed from a single sheet of material bent back upon itself, the inner 25 part of the bend serving as the edge of a guide formed by the base, the upper folded back part of the base having a piece cut away adjacent the 30 fold through which the blade may pass to enter the guide, and the lower folded back part of the base having a bowed or undulating part provided in register with the opening in the upper base part serving as the guide for that part of the 35 blade projecting through the plane of the guide or handle.

5. An edge trimmer for paper and like materials, comprising a base part formed from a single sheet of material bent back upon itself, the inner 40 end of the bend serving as the edge of a guide formed by the base, the upper folded back part of the base having a piece cut away adjacent the fold to provide an opening through which the blade may pass to enter the guide, the material adjacent the cut-away part being bowed upwardly to provide a carrier for the transversely 45 adjustable slide, said bowed part carrying adjustable means for retaining the slide in engagement therewith.

6. An edge trimmer for paper and like materials, comprising a base part serving as a handle and guide, said base part being formed of a single piece of material and bent upon itself, a transversely adjustable slide carried by said base part 55 and a blade rigidly carried by said slide with a cutting edge inclined to and projecting into the guide to intersect the plane of material therein, said slide and blade-carrying part being formed from a single piece of material, the blade-carrying 60 part being disposed in a plane intersecting that of the remainder of the slide.

ARTHUR ALEXANDER GELLEFF.
